UNITED STATES PATENT OFFICE.

FRANK B. BARBER, OF FULTON, ILLINOIS.

WORK-HOLDER.

1,125,253.

Specification of Letters Patent.

Patented Jan. 19, 1915.

Application filed April 23, 1914. Serial No. 833,949.

To all whom it may concern:

Be it known that I, FRANK B. BARBER, a citizen of the United States, residing at Fulton, in the county of Whiteside and 5 State of Illinois, have invented certain new and useful Improvements in Work-Holders, of which the following is a specification.

My invention relates to work holding devices adapted for use in a wide variety of 10 arts, and has for its object the provision of a plurality of vises, each of which is adapted to hold separate objects or different parts of the same object, said vises being simultaneously movable relatively to each 15 other along a longitudinal axis and further being movable independently in a direction transverse to said first mentioned axis, whereby articles held in said vises may be retained in the proper positions to enable 20 them to be operated upon by a workman, thus leaving both his hands free to facilitate the manipulation of his tools, or whereby different connected parts of an object held by the vises may be separated by the movement 25 of the vises away from each other.

An important object is the provision of the aforementioned means for moving the vises transversely of the main axis, whereby, when the different parts of objects held 30 within the vises are of different sizes, either or both vises may be moved transversely of the longitudinal axis of movement so that separation of the vises will cause the strain upon the objects to be exerted in a direction 35 parallel to the longitudinal axis of movement.

With these and other objects in view, such as simplicity, durability, efficiency, and the general improvement of the art, my invention 40 consists in the novel construction and arrangement of parts as hereinafter described and claimed and illustrated in the accompanying drawings, in which:

Figure 1 is a front elevation of my device, and Fig. 2 is a cross section thereof.

Referring more particularly to the drawings, the numeral 1 designates the supporting base of the structure. This base 1 comprises a flat plate 2 having a dove-tailed 50 tongue 3 on its upper surface, and upstanding ears 4 on its ends. In these ears 4 are openings for the passage of a rod 5 which has on one half of its length a right hand screw thread 6 and on the other half a left hand screw thread 7. On one end of the

rod 5 I provide a handle 8 for rotating the rod.

My improved vises are disposed upon the base 1, one being disposed upon the right hand screw-threaded portion 6 and the other being disposed upon the left hand screw-threaded portion 7 of the rod 5. Each of the vises comprises a base block 9 provided upon its lower face with a dove-tailed groove 10 for the reception of the tongue 3 on the base 1. The upper face of the block is provided with a tongue 11 which is disposed within a corresponding dove-tailed groove formed in the bottom portion of the upper section 12 of the vise. 70 The upper section 12 comprises the usual movable jaw 13 and the fixed jaw 14 operated by the usual screw and handle 15. The upper section 12 of each vise is moved upon the base block 9 by means of a screw-threaded rod 16 passing through the block 9 and provided upon its end with an operating handle 17. The upper section 12 is further provided at its forward portion with a downwardly extending apron 18 provided with an aperture 19 for the passage of the reduced end 20 of the screw 16. 75

From the foregoing it will be seen that the vises being in the position shown in the drawings, rotation of the handle 8 and consequently the rod 5, will cause the vises to be moved toward or away from each other depending upon in which direction the handle 8 is turned. It will also be observed that rotation of the handle 17 will cause the upper section 12 of either vise to be moved upon the base block 9 in a plane at right angles to the axis of the previously described longitudinal movement. 85

In use for instance when it is desired to 90 braze or solder two metallic pieces to each other the pieces are gripped between the jaws 13 and 14 of the vises which are then separated or brought together as required by moving the handle 8 until the ends or 100 other desired portions of said metallic pieces shall come into contact whereupon the brazing or soldering may be readily accomplished by the operator. This device may be used for a wide variety of purposes more or less analogous to the instance mentioned. The device may be advantageously used for straightening wires, rods, shafts and the like, by gripping the ends between the jaws 13 and 14 and then turning the handle 8 to 110

separate the vises, thus causing longitudinal strain upon the rod or wire, as desired. Another use to which the device may be advantageously put is the separation of 5 articles which have been glued or shrunken together or secured in any other manner. This action is accomplished by gripping the portions to be separated between the jaws 13 and 14 and then rotating the handle 8 10 for moving the vises apart.

The fact that the upper sections 12 of the vises may be moved upon the base block 9 is of great importance as for instance if 15 two objects to be stretched or pulled apart are of different sizes it is necessary to move one or both of the upper sections 12 upon the base block 9 in order that the separating strain may be exerted in alinement with the longitudinal axis of the base 1 and rod 20 5 as otherwise the separating strain would not be uniform and would be lacking somewhat in efficiency.

Having thus described my invention what I claim is:

25 1. A work holder comprising a base, a pair of vises slidably mounted on said base, and mechanical means for moving said vises longitudinally and transversely.

30 2. A work holder comprising a base, a pair of vises slidably mounted thereon, and means for moving said vises longitudinally and transversely, said means comprising one screw connecting both vises for longitudinal movement on said base and one screw 35 on each vise for transverse movement on the base block of said vises, and means for causing a simultaneous movement of said vises toward or from each other.

40 3. A work holder comprising a longitudinal relatively stationary base and vises adapted to fit on said base, said vises having jaws at their tops operated by a screw rod, and adapted to move longitudinally on said base by means of a screw rod provided with 45 right and left hand screw-threaded portions, and each of said vises having a screw rod inserted for transverse movement on their base blocks.

50 4. A work holder comprising a longitudinal base, a pair of vises slidably mounted thereon longitudinal thereof, screw operated means for moving said vises, jaws at the top of said vises and screw rods for operating said jaws, and means for moving the upper sections of said vises in a direction at right angles to the axis of said base, said last mentioned means comprising 55

a screw rod passing through the base blocks of the vises.

5. A work holder comprising a base, a plurality of vises slidably mounted thereon, screw operated means for simultaneously moving said vises toward or from each other, and means whereby the body portions of said vises may be moved in a 65 direction at right angles to the axis of said base, said means comprising threaded screw rods passing through the base blocks of said vises.

6. A work holder comprising a base, a 70 pair of vises slidably mounted thereon, and a rod provided with right and left hand screw-threaded portions, each portion engaging one of the vises whereby said vises may be simultaneously moved toward or 75 from each other, each of said vises comprising a relatively stationary base, and a body section slideable upon said base portion in a direction at right angles to the direction of bodily movement of said vises. 80

7. A work holder comprising a longitudinal base, vises slidably mounted on said base, each of said vises having a base block, a body portion slidably mounted on said base block movable transversely of said longitudinal base, and screw operated gripping jaws on said body portion. 85

8. A work holder comprising a longitudinal base, a dove-tailed tongue on said base, a plurality of vises slidably mounted on 90 said base, each of said vises having base blocks, said base blocks having dove-tailed slots for slideable connection with said dove-tailed tongue on said longitudinal base and screw means for simultaneously operating 95 said vises.

9. A work holder comprising a longitudinal base, a plurality of vises slidably mounted on said base, each of said vises having a base block, a body portion, and 100 screw operated gripping jaws, said base block having a dove-tailed tongue on its upper face, and said body portion having a dove-tailed groove for slideably connecting with said base block, and screw means for 105 moving said body portion on said base block transversely of said longitudinal base.

In testimony whereof I hereto affix my signature in the presence of two witnesses.

FRANK B. BARBER.
